CLAIM

I claim the ornamental design for a swivel charging station, as shown and described.

DESCRIPTION

FIG. 1 is a perspective view of my new design for a swivel charging station;

FIG. 2 is a side perspective view thereof;

FIG. 3 is a front elevation view thereof;

FIG. 4 is a side elevation view thereof, the other side elevation view is a mirror image of that shown;

FIG. 5 is a rear elevation view thereof;

FIG. 6 is a top plan view thereof;

FIG. 7 is a bottom plan view thereof; and,

FIG. 8 is a cross-sectional view of the swivel charging station shown in FIG. 1 taken along line 8—8.

The broken lines shown in the drawings are for illustrative purposes only and form no part of the claimed design.
